Des. 219,979
Patented Feb. 23, 1971

219,979

DENTAL HANDPIECE

Ronald G. Coss, 2320 McCart Ave.,
La Habra, Calif. 90631

Filed Jan. 2, 1970, Ser. No. 20,738

Term of patent 14 years

Int. Cl. D24—03

U.S. Cl. D24—1

FIG. 1 is a side elevational view of a dental handpiece showing my new design;

FIG. 2 is an elevational view of one end thereof;

FIG. 3 is an elevational view of the opposite end;

FIG. 4 is a fragmentary sectional view, taken substantially on line 4—4 of FIG. 1; and

FIG. 5 is a fragmentary sectional view, taken substantially on line 5—5 of FIG. 1.

I claim:

The ornamental design for a dental handpiece, substantially as shown.
